DISPLAY HOLDER

Harry Stacy Ford, Cleburne, Tex.

Application February 9, 1937, Serial No. 124,912

2 Claims. (Cl. 211—49)

This invention relates to display holders and particularly to display holders of the type made use of by merchants in displaying for sale stacks of articles such as neckties and socks.

It is generally customary in merchandising articles of this class to arrange the socks or ties, or light articles, in groups of a common size, common style or common price, and it is highly advantageous to prevent intermingling of articles of different groups, which, unless precautions are observed, frequently occurs accidentally when the articles are inspected or handled by prospective customers. It has been proposed that the several groups or piles of ties and the like may be maintained separate by the use of individual holders for such groups and one form of holder made use of for this purpose comprises a simple flat base member, having a surface upon which a pile or stack of articles may be disposed and retaining guards for laterally confining the pile. It has been found, however, that while a stack of articles, for instance socks, when originally placed in position will present a neat and attractive appearance to prospective customers, the pile or stack of articles will not be adequately retained in position by any of the restraining devices now commonly used and that they will slide from the display devices unless such devices are provided with restraining means which so envelop the socks that the attractiveness of the display is markedly decreased. It is the purpose of the present invention to provide a display holder of simple type, inexpensive to construct, and yet which supports and retains the articles to be displayed and sold in an entirely adequate manner, and without at the same time concealing the articles from view to any substantial extent. In accordance with the present invention also means is provided for minimizing the possibility of surreptitious removal of articles or theft from the display holders upon which they are placed, an advantage of considerable importance.

It is a further object and advantage of the invention to so construct the novel holder that, while the articles displayed may be removed singly from time to time until the holder is empty, a suitable legend, which may be a manufacturer's name or slogan, price mark, grade mark, or other information for a prospective purchaser, is at all times placed permanently upon the upper surface of the uppermost article in the stack retained upon the holder. It has heretofore been found almost impossible to maintain suitable identifying legends closely associated with stacks of such articles in holders of the class described.

In accordance with the present invention, however, this may be easily done and the advantages flowing from this feature of the invention will be apparent to all who are called upon to make use of such devices.

A preferred form of the invention will be disclosed by way of example, this form being fully illustrated in the accompanying drawing, in which

Figure 1 is a perspective view of a display holder embodying the invention;

Figure 2 is a side elevation of the same; and

Figure 3 is a fragmentary view, partially in section, of a display holder having a somewhat modified form of article retaining means.

The display holder illustrated is in many particulars of conventional type comprising a base 10 which is preferably of light weight as when fabricated of wood and which may have any desired outline. The base 10 shown is primarily intended for the reception of a pile of socks such as indicated at 11, and has a reduced end 19 having a width only slightly greater than the top of a folded sock the remainder of the base being somewhat wider, and the end of the larger portion remote from the reduced portion 19 having some ornamental configuration, such as indicated at 10².

Guard members are indicated at 12, these guard members being fabricated of wire and being generally U-shaped, the ends of the wire being inserted in suitable apertures provided for their reception in the base member 10. The guard members are intended to prevent sliding of individual socks, or of the pile of socks, off of the base member, and do to a substantial extent. However, as pointed out before, the guards 12 cannot in and of themselves wholly prevent this sliding movement or displacement and it is not possible to wholly surround the pile of socks with guards since the articles cannot in such cases be as advantageously displayed.

In accordance with the present invention an additional member is provided for positively retaining the pile of articles upon the display holder. While this additional member may be formed in various ways, it may conveniently comprise a generally U-shaped member 13, fabricated for instance of wire, the free ends of the member being inturned and loosely received within apertures formed in the base 10 so that the member may be said to be pivotally attached to the base for rocking movement about an axis just below and parallel to the upper, or article receiving, surface of the base. Member 13 may be said to have two generally parallel leg por-

tions 13' and a transverse midportion 13² connecting the leg portions, the transverse portion 13² being preferably formed as a loop and the plane of the loop being disposed at a slight angle 5 to the plane of the leg portions, as shown in Figure 2. Means is preferably provided for retaining the looped portion 13² of member 13 in the position in which it is shown in Figures 1 and 2, i. e., this portion resting upon the upper 10 surface of the uppermost article of a stack of articles resting upon the base 10. The loop is so disposed angularly with respect to the leg portions 13 that it preferably lies substantially horizontally upon the upper article. The loop 13² 15 also comprises a suitable base for the attachment of an advertising placard such as indicated at 14 the attachment being made in any suitable manner and upon the placard, which may be a piece of pasteboard or the like, may be written 20 any suitable advertising indicia, grade marks, size numbers or other information of interest to the merchant or prospective purchasers.

The advertising placard will remain substantially parallel to the base 10 during the time 25 that the device is in use although its angularity will change somewhat with the height of the pile of articles upon which it rests. It will be appreciated that advertising cards of various types may be used and that they may be secured 30 to the loop 13² in various ways, also that the cross member 13² may be so disposed as to make substantially a right angle with the base at all times instead of being substantially parallel, considerable variation of the invention in this respect being permissible in order that the wishes 35 of various users of the display holder may be met.

Preferably means is provided for maintaining close contact of the portion 13² of the member 13 with the uppermost article of the pack. In 40 the form of the invention shown in Figures 1 and 2 resilient springs are made use of for this purpose, one such spring being indicated at 15. Spring 15 has one end 15' attached to the base 10, its opposite end 15² attached to the adjacent 45 leg 13' of member 13 and its intermediate portion coiled about the inturned portion of leg 13'. Springs 15 serve to maintain loop 13² in rather tight contact with the uppermost article of the pile 11 so that the pile is firmly retained in position upon the base 10. If desired 50 the customary guard members 12 may be dispensed with since the swinging member 13 will adequately retain a substantial pile of articles upon the base 10 without the assistance of stationary guards. It is of course easy to remove 55 any one of the stack of articles by simply rocking the member 13 upwardly about its pivotal axis to release the same. The member 13, however, is pressed downwardly with sufficient force to

render it difficult to remove an article surreptitiously and without lifting the same, thus discouraging theft or unauthorized removal.

If desired, means may be provided for more positively securing member 13 in article retaining position, for instance the lower ends of the legs 13' may be provided with loops or eyes 16 which encircle the shank of a bolt 17 positioned within a cylindrical aperture formed in the base 10. Bolt 17 is provided at one end with a head 10 17' and its other end is threaded at 17², a wing nut 18 having threaded engagement with the threaded end of the bolt.

Upon tightening of the wing nut 18, the ends 15 16 of member 13 are tightly gripped by the bolt 15 head 17' and the wing nut 18 respectively, being forced against the adjacent faces of the base 10. Member 13 is therefore frictionally retained in position and no article may be conveniently removed without loosening of the wing nut 18. If 20 desired means for positively locking member 13 in article engaging position may be adopted but in the average case such positive locking means is not necessary.

Obviously the swinging retaining member 13 25 may be pivotally attached to either end of the base 10 and, as has been previously explained, its exact shape and the material from which it is fabricated may be varied to suit circumstances.

Having thus described the invention, what is 30 claimed as new and desired to be secured by Letters Patent is:

1. In a display holder for ties, socks, or similar articles, in combination, a base member having a surface for supporting a stack of articles, a 35 bail formed of a single, continuous generally U-shaped wire or rod, the open end of the U being pivoted to said base about an axis substantially parallel to and below said surface, the free end of said bail having a reentrant bight, the said 40 bight lying in a plane at an angle to the plane of said U, a flat plate secured to and filling said bight, said bight and plate being adapted to contact with and lie flat upon the uppermost article of a stack resting on said base. 45

2. In a display holder for ties, socks, or the like, in combination, a base of similar size and configuration as the articles and having a surface for supporting a stack of such articles, stationary guards at the lateral edges of said base extending 50 vertically upwardly therefrom, a bail pivoted to said base about an axis substantially parallel to and below said surface, said bail passing between and guided by at least one set of oppositely disposed stationary guards, the free end of said 55 bail having means to support a plate at an angle to the rest of the bail to rest substantially flat upon the topmost article in a stack.

HARRY STACY FORD.
